UNITED STATES PATENT OFFICE.

GEORGE L. RICE, OF CHICAGO, ILLINOIS, ASSIGNOR TO INTERNATIONAL HARVESTER COMPANY, A CORPORATION OF NEW JERSEY.

TWINE BALL.

Application filed October 12, 1925. Serial No. 61,874.

This invention relates to twine balls of the kind used in grain binders for the harvesting and binding of sheaves of grain. More particularly it relates to a twine ball 5 having a cover, which cover is designed to prevent collapse of the ball and to prevent snarling of the twine as the ball is unwound. A covered twine ball of this general kind is disclosed in applicant's prior Patent No. 10 1,340,254 of May 18, 1920.

The purpose of covering the ball as described in applicant's prior patent was to provide a ball of twine containing the maximum amount of twine in a given space and 15 of such formation that the ball would resist lateral strains which tend to cause longitudinal bulging during handling and shipping and its collapse in the final stage of unwinding of the ball and in this manner 20 preventing snarling and tangling.

The twine ball comprises a cylindrical main body having the well known "universal" form of winding, said body having flat ends wound around the spindle of a "universal" winding machine, the cover therefor 25 preferably being a continuation of the same strand of twine but wound lengthwise around the ball in a direction at a slight angle to the longitudinal axial, hollow opening 30 of the ball, which remains after removal of the ball from the spindle of the winding machine. In so covering the ball the flat end faces of the same are also covered, which is 35 advantageous in preventing endwise bulging or expansion of the body of the ball when the balls are stacked or roughly handled in shipping the same. In the ball of the prior patent a circular uncovered area concentric with the axial opening and of greater area 40 than the opening was left at each end of the finished ball, one uncovered area being larger than the other. Because of this construction, of necessity the angle between the runs of the strand of twine forming the 45 cover and the longitudinal axis of the ball through its opening was relatively large. Because of this relatively large angle the runs of the cover had a tendency to slough or slip off the ball during handling.

50 The covered ball of the present invention is designed to overcome this tendency of sloughing by obtaining an acute angle of the strands forming the cover with respect to the axis of the ball.

55 By providing these uncovered areas of

different sizes the balls readily nest when stacked end to end for shipping. In this manner a minimum of cubical space is occupied. This nesting idea is also carried out equally advantageously in the ball of 60 the present invention. The cover strands are wound at the minimum angle with respect to the axis of the ball, consistent with retaining the nesting advantage.

As is well known in this art the twine ball 65 has a free inner end which lies loosely in the axial opening, said end being connected to the tying mechanism of the grain binder so that the twine is taken first from the center of the ball to unwind it from the opening outwardly. A frequent mistake made by farmers is to pull this free inner end of the strand out of the opening from the wrong end of the ball, whereupon the grain binder must pull the twine out of the ball against 70 the twist of the strand rather than with the twist, which error is another frequent cause of snarling and tangling of the twine. Such mistake obviously can be made with 75 covered as well as with uncovered balls, and 80 in the covered ball of the present invention it is an object so to arrange the cover that the proper end of the ball from which withdrawal of the twine shall take place will be indicated and in fact, regardless of such indication, to make incorrect withdrawal awkward and unnatural, by making the free inner end of the strand in the opening difficult of access from the wrong end of the ball, all to the end that the twine will be 85 properly removed and vexatious delays in the field due to this common mistake will be overcome.

Grain binders are provided with a twine supply can which receives two or more balls 90 of twine, said balls being placed properly in the can, one on top of the other and end to end, in such a manner that the topmost ball supplies the demand of the binder until it is exhausted and then the next ball automatically is started. This method of successively using the balls is accomplished by initially tying together the outer end of the top ball and the inner end of the ball next below it. The practice just described is prolific of 100 further trouble, as in the case especially of uncovered balls, two adjacent balls will become entangled before the topmost ball is completely consumed. This happens because 105 the unwinding twine from the inside of the 110

top ball rises and falls in the ball opening, in response to intermittent demands made upon it by the grain binder, and this loose strand often works its way down into the opening 8 of the ball below, and there, due to loose fibers in the twisted strand, it will pick up the strand of the lower ball and start pulling on it to unwind the lower ball before the upper ball is consumed.

10 Another object of the present invention is to overcome this difficulty by so forming the cover that it is practically impossible for adjacent balls arranged in the twine can of the grain binder to become entangled with 15 each other.

Still another object is to provide an improved cover for such twine balls which will maintain its upright position after the universal winding of the ball has been removed.

20 All of these advantageous objects are achieved briefly in the provision of a twine ball having a cover whose runs are wound at the minimum acute angle produced by carrying the cover at the bottom end of the ball 25 to the edge of the axial opening of the ball, so that the strands extending from said edge to the diametrically opposite part of the edge of the cover at the upper end of the ball, which is spaced from the opening, shall 30 closely approach parallelism with the vertical axis of the ball.

Referring now to the accompanying sheets of drawings, there is shown an illustrative embodiment of the invention, wherein like 35 characters of reference designate like parts throughout the views, and in these sheets of drawings,—

Fig. 1 is a side view of two stacked balls as they would appear when arranged in the 40 twine can of a grain binder, a portion of the cover of each ball being removed and the lower ball being partly in section to show the universal center winding and the axial openings;

45 Fig. 2 is a side elevation of the improved twine ball illustrating the angle of wind of the strand formed into the cover;

Fig. 3 is a perspective view showing the 50 cover after the universally wound body of the ball center and a portion of the cover have been unwound from the center of the ball;

Fig. 4 is a bottom end elevational view of the ball; and

55 Fig. 5 is a top end elevational view of the same ball.

The inner or body part winding of the ball illustrated is of the well known type of universal winding common in this art, and, therefore, it will not be described in detail. Suffice it to say that this inner winding is close and compact and contains the maximum amount of twine for the space occupied;

60 As is well known the main winding is

formed on a spindle by means of spiral turns of twine which run back and forth with respect to the length of the ball. In the drawings a main winding or body 10 is shown and upon the completion of the winding of this part there remains of necessity, projecting portions 11 which constitute the outer turns of the strand of twine, and it has been found that these projecting portions are the cause of part of the trouble 70 resulting from snarling and collapsing. For the purpose of supporting these outer turns and also to prevent end deformation or longitudinal bulging of the ball due to lateral pressures resulting from rough handling and the like, there is provided an outer open mesh or cover winding 12, which is preferably an unbroken continuation of the strand forming the main winding 10, said cover being tightly wound around the cylindrical body of the inner ball 10 and, as shown, is preferably of open formation.

Upon removal of the finished ball from the spindle of the balling machine, there will be left in the ball, a central axial opening 90 13 of substantially uniform diameter and, as shown in Figs. 1 and 5, there can be seen the free end 14 of the strand forming the start of the ball, said free end lying loosely in the hollow core from whence it may be 95 pulled out from the proper end of the ball, as will later appear, to start unwinding of the ball, it being understood that the ball is unwound from the opening outwardly, so that the cover winding always remains to the last, as shown in Fig. 3. The end walls of the cylindrical body 10 are flat, as at 13' (see Fig. 1), and the strands in the cover winding fit closely against these flat ends, leaving, however, at the top of the ball a 100 circular uncovered area 15. At the opposite or bottom end of the ball the cover extends to and is flush with the opening 13 (see Fig. 4). It should be noted that the turns forming the cover at the ends are oppositely 105 disposed and run in a direction tangential to the opening of the ball.

In the ball of applicant's previous patent, both ends embodied an uncovered area. In forming the cover it was, therefore, necessary 110 to have the turns of twine form a relatively large angle with respect to the axis of the ball running longitudinally through the opening and, as a result, sloughing of the cover strands off the ball sometimes occurred. In the ball of the present invention it will be noted that the cover extends to the edge of the axial opening at the bottom end of the ball, which permits the turns of the cover to be wound more nearly in line with the 115 axis of the ball. In other words, the angle shown in Fig. 2 between the axis A—B of the ball and a line C—D passing through a turn of the cover is approximately 20 degrees or less, which is sufficient to overcome the 120 125 130

sloughing off tendency of the cover strands. This cover winding, obviously, will exert a truss action permitting the ends of the cover to exert forces inwardly on the flat ends of the ball to overcome any tendency of the said ends to bulge out longitudinally.

It will be observed that in forming the cover the twine builds up in the form of an annular thickened or beaded portion 16 at 10 the top of the ball and a similar portion 17 at the bottom of the ball. The end which is provided with an uncovered area is the top end of the ball and no confusion over this can possibly arise, as the present ball has 15 only one end which is partly uncovered, whereas in the ball of the prior patent mentioned both ends were provided with an uncovered area. Thus, that end of the present ball having an uncovered area clearly indicates to the user, once the fact is known, 20 that it is the top side of the ball and that the free end 14 of the twine should be pulled out at that end. Also, quite obviously, because of the beaded portion 17 closely surrounding the core at the bottom of the ball, 25 it would be awkward and unnatural to withdraw the twine end 14 from that end of the ball. Furthermore, in placing these improved balls end to end in a twine can of 30 a grain binder or in shipping containers, it is apparent that adjacent balls can be made to nest together by telescoping the bottom small end and bead 17 of an upper ball into the larger top bead 16 of a lower ball. (See 35 Fig. 1.)

In Fig. 1 there is shown the manner of stacking and connecting these balls in a twine can, the can not being shown. The free end 14 of the upper ball feeds out of 40 the core as already stated. The outer free end indicated at 18 in Figs. 1 and 4, which terminates the cover of the ball, is tied, as shown at 19, to the free end 14 of the lower ball, so it will be seen that when the upper 45 ball is exhausted the lower one is immediately brought into play.

In the case of uncovered balls, a serious difficulty is encountered when coupling several balls together in this fashion. The 50 demand and pull of the grain binder tying mechanism on the free end 14 is, of course, intermittent and this causes the said end at times to sag in the form of a bight, which 55 plays up and down in the opening of the ball. Frequently it plays down into the opening of the adjacent lower ball and because of the multitude of loose fiber ends in the strand, the twine interengages and braids with similar loose fiber ends in the 60 free end 14 of the said lower ball, which results in starting unwinding of the lower ball before the upper one has been completely consumed. Under these conditions it takes but a moment to create a tangle,

which, of course, is very vexatious and objectionable. A very important advantage gained by using the present ball is that this difficulty is completely overcome because of the bottom of the balls having their entire area, with the exception of the opening covered. Experience has shown that the end 14 as it is unwound will not play down into the opening of the lower ball because of the presence of the beaded or thickened portion 17, which acts like a stop and prevents this play down into the lower ball. Here it should be borne in mind again that the twine strand is covered with projecting free fiber ends and, because of the multiplied strands forming the bead 17, 80 these free fiber ends also are multiplied, thereby serving as a better seal to prevent the end 14 from going down into the core of the lower ball.

Another feature of the present ball is the ability of the cover to stand to the last, even with the entire inside of the ball removed, without collapsing and forming a snarl. In this connection attention is directed to Fig. 3. Here a part of the cover remains after 90 most of the ball has been unwound. Of course, it must be remembered that the cylindrical twine can, not shown, helps the cover to support itself, as shown. In this figure it will be seen that a twisted clam shell effect is produced with the sides of the clam or shell oppositely disposed and twisted from the hinge portion at the bottom in an outward and upward direction indicated 95 generally at 20, where the cover is flush with the opening of the ball. Thus, as the cover unwinds, the lower turns from the hinge 20 successively support the upper strands forming the top side or ceiling of the vacated cover, thereby effectively preventing collapse of the cover top and insuring that 100 all of the twine of the cover will be run out without causing a tangle.

From the above description, it must now be appreciated that an improved covered ball 110 has been provided, which achieves all of the objects sought, and possesses many advantages which are desirable in view of the many practical difficulties heretofore encountered in twine balls now known in the 115 art.

What I claim is:

As an article of manufacture, a ball of twine having a cylindrical body and flat ends and having a cylindrical axial opening therethrough, and having a cover winding which at one end of the ball is spaced from the edge of the opening to leave an uncovered area surrounding said opening, the cover winding at the other end of the ball extending to the edge of the opening.

In testimony whereof I affix my signature.
GEORGE L. RICE.
